UNITED STATES PATENT OFFICE.

MAGNUS SWENSON, OF CHICAGO, ILLINOIS, ASSIGNOR, BY MESNE ASSIGNMENTS, TO CENTRAL TRUST COMPANY, OF NEW YORK, TRUSTEE, A CORPORATION OF NEW YORK.

FIRE-EXTINGUISHING ATTACHMENT FOR COTTON-GIN PLANTS.

SPECIFICATION forming part of Letters Patent No. 715,219, dated December 2, 1902.

Application filed February 18, 1901. Serial No. 47,796. (No model.)

To all whom it may concern:

Be it known that I, MAGNUS SWENSON, a citizen of the United States, residing at Chicago, in the county of Cook and State of Illinois, have invented a certain new and useful Improved Fire-Extinguishing Attachment for Cotton-Gin Plants, of which the following is a description.

My invention relates to an improved fire-extinguishing attachment for use in connection with cotton-gins; and my object is to provide and produce a simple and effective device for the purpose and one that can be very quickly brought into operation.

In modern ginning plants the fine fluffy fibers from the gins are blown through a closed trunk or flue to a condenser, by which the lint is separated from the blast and formed into a sheet or bat. The presence of pieces of stone, iron, and other hard substances in the seed-cotton frequently results in sparking, which ignites the tinder-like fiber, and the conflagration rapidly spreads along the lint-flue, so that in a very short time much damage may be done. Most of the modern gins are provided with means whereby live steam may be admitted into the trunk or flue and into the condenser itself for extinguishing any fires therein; but experience has shown that such means are seldom efficient and, in fact, are often directly objectionable on account of the heat of the escaping steam.

Broadly stated, my invention consists in the combination, with the trunk or flue through which the fiber is conveyed from the gins to the condenser, of means for generating carbonic-acid gas and for liberating the same into said trunk or flue, whereby a non-combustion-supporting atmosphere will be developed therein, so that any fire will be readily and effectively extinguished.

In its preferred instance, my invention comprises a receptacle connected with the lint flue or trunk and containing a suitable chemical adapted to generate carbonic-acid gas when acted on by an acid, the latter being carried in a glass vessel within the receptacle, adapted to be broken by the operation of a plunger, so as to free the acid and liberate the

gas, permitting the latter to enter the trunk or flue.

In order that my invention may be better understood, attention is directed to the accompanying drawing, forming a part of this specification and showing in section a trunk or flue connecting a battery of gins with the condenser equipped with the preferred embodiment of my invention.

In the drawing, A represents a gin or battery of gins of any suitable type, B a flue leading from the gin or gins and through which the lint-cotton is blown by the draft, and C a condenser or other bat-former for separating the blast from the cotton and forming the latter in a sheet or bat. Supported from the trunk or flue B is a closed metallic receptacle D, having, preferably, a light pivoted cover E, opening upwardly. Supported within the receptacle D is a vessel F, made preferably of glass, and arranged opposite to said vessel is a plunger G, which may be forced or driven inward to break the vessel. At the bottom of the receptacle D may be placed a mass H of a suitable chemical, such as sodium bicarbonate, adapted to generate carbonic-acid gas when acted upon by an acid. This acid—as, for instance, sulfuric acid—may be contained in the vessel F.

In operation, in the event of a fire in the trunk or flue or in the condenser the feed of cotton to the gins will be immediately stopped, although, if desired, the draft therefrom may be continued to force the fire along the trunk or flue. The plunger G is now forcibly pushed or driven inward, breaking the vessel F, liberating the acid, and resulting in the generation of carbonic-acid gas, which in flowing upward will elevate the valve E and pass into the trunk or flue. The draft passing through the trunk or flue will dissipate the carbonic-acid gas, which will rob the draft of its combustion-supporting quality. Since from two and a half to three per cent. of carbonic-acid gas is sufficient to stop combustion, a relatively small amount of the gas generated in the receptacle will be effective for the purpose.

Having now described my invention, what

I claim as new, and desire to secure by Letters Patent, is as follows:

1. The combination with a gin, a condenser, and a flue connecting the gin and the condenser, of a receptacle connected to the flue and supplied with chemicals for the generation of carbonic-acid gas, and means for normally stopping communication between the receptacle and flue, substantially as set forth.
- 10 2. The combination with a gin, a condenser, and a flue connecting the gin and the condenser, of a receptacle connected to the flue and

supplied with chemicals for the generation of carbonic-acid gas, and a pivoted valve or flap normally stopping communication between the receptacle and flue, substantially as set forth.

This specification signed and witnessed this 25th day of January, 1901.

MAGNUS SWENSON.
